UNITED STATES PATENT OFFICE.

HORACE LEOPOLD TUCKER BUCKLE, OF YIEWSLEY, ENGLAND.

DIAPHRAGM-HOLDING RING FOR TALKING MACHINES AND OTHER ACOUSTICAL INSTRUMENTS.

Application filed February 23, 1924. Serial No. 694,719.

To all whom it may concern:

Be it known that I, HORACE LEOPOLD TUCKER BUCKLE, a subject of the King of Great Britain, residing at Yiewsley, in the county of Middlesex, England, have invented new and useful Improvements in Diaphragm-Holding Rings for Talking Machines and Other Acoustical Instruments, of which the following is a specification.

10 This invention relates to improvements in rings for holding the diaphragm of talking machines and other acoustical instruments, where the diaphragm is mounted in and carried by the holding ring itself, instead of being clamped by a ring to the body of a sound box or telephone transmitter for example. The invention is particularly applicable to rings for holding large diaphragms such for example as those described 20 in British Letters Patent No. 11,015 of 1909 where the diaphragm may be as much as 10 or 14 inches in diameter. It is of great importance that the ring in which the diaphragm is mounted should be at once strong, 25 rigid and light so that while it has little or no tendency to respond to the vibrations transmitted to the diaphragm it is nevertheless of such a weight as not to throw too much work upon the needle point or other 30 means whereby the diaphragm, in a talking machine for example, is moved over the record.

According to the present invention a diaphragm holding ring for acoustical instruments is composed of a strip or strips of metal or other suitable stiff material folded over the edge of the diaphragm and gripping the diaphragm on both sides and it has a stiffening rib running round it which 40 strengthens the ring against distortion out of its normal plane that is to say, the plane of the diaphragm. The ring when closed on the diaphragm may have a section formed of two flat sides lying close on either side of 45 the diaphragm between which is a channel portion running round the outside of the ring and forming the stiffening rib.

The ring may be formed by shaping a flat strip of aluminium for example into a ring with a substantially V-section and with a channel portion at the point of the V. The ends of the strip may be stepped, so that when the ring is closed down on the diaphragm the overlapping edges at the two ends may be held together by a bolt or rivet;

while there may be laid in the channel portion at the abutting ends a tie member with a roughened surface, such for example as a short roughened rod, on which when the ring is closed down on the diaphragm the inner sides of the channel portion grip fast.

The invention is illustrated in the accompanying drawings in which Fig. 1 is a fragmentary perspective view showing the abutting ends of the ring, before closing, separated from one another, and the tie member for use therewith.

Fig. 2 shows a section on an enlarged scale of the ring before closing.

Fig. 3 shows a section on an enlarged scale 70 of the ring when closed down upon the diaphragm with the tie member in position.

A flat strip of aluminium is first formed up into a ring with the section shown in Fig. 2, that is to say substantially a V-shaped 75 section with the flat sides *a a* and a channel portion *b* at the point of the V, the sides extending inwardly from the channel portion toward the center of the ring. The ends of the rings so formed are stepped at *c*, as 80 shown in Fig. 1, so that the end *d* on the right hand side overlaps the end *e* on the left hand side. In these overlapping ends are drilled holes *f* through which a bolt *g* may be inserted when the ring is closed down 85 on the diaphragm. The tie member *h* consists of a relatively short section of roughened rod which is housed within the channel portion *b* and spans the joint between the abutting ends of the ring. This tie member 90 is preferably slightly curved to correspond with the curve of the completed ring. When the ring is closed down upon the diaphragm *i* as shown in Fig. 3 (by means of a suitable press) the tie member *h* is gripped tightly 95 by the sides of the channel portion *b* and the ends of the ring cannot be drawn apart. The set screw *g* completes the joint. Between the holding ring and the edge of the diaphragm may be inserted a folded ring of felt 100 or rubber *k*, so that the diaphragm is insulated from the metal rim.

It will be seen that the completed ring (Fig. 3) shows a means of holding the diaphragm *i* which is light and strong. The section of the closed ring presented by the flat sides *a a* holds the ring against distortion from the true circular form whilst the circumferential rib formed by the closed channel portion *b* offers sufficient resistance 110

2

to any distortion of the ring from its normal plane, that is, the plane of the diaphragm. In the closed or operative position of the ring the channel portion projects both beyond the periphery of the diaphragm in the plane of the latter and laterally beyond the sides *a a*.

It will be understood that the ring in the case of a talking machine can be secured to suitable holding means such as a spider, at the centre of which is mounted the reproducing stylus, the screws for attaching the ring to the ends of the spider arms passing through both the flat sides *a* of the ring and tending still further to stiffen the ring.

I claim:

1. A diaphragm holding ring having a channel portion extending around its circumference and flat annular sides extending inwardly from said channel portion toward the center of the ring and adapted to engage opposite faces of the diaphragm, said channel portion projecting both beyond the periphery of the diaphragm in the plane of the latter and laterally beyond said sides, when the ring is in an operative position, and forming a circumferential strengthening rib.

2. A diaphragm holding ring having spaced gripping surfaces adapted to engage opposite faces of the diaphragm and an intermediate channel portion extending around the periphery of the ring and forming a circumferential strengthening rib, the ring being split and having abutting ends, and a relatively short tie member housed within the channel portion and spanning the joint between said ends and in intimate binding connection with said ends to prevent separation thereof.

3. A diaphragm holding ring having spaced gripping surfaces adapted to be pressed towards each other into engagement with opposite faces of the diaphragm, and an intermediate channel portion extending around the periphery of the ring, said ring being split and having abutting ends, and a roughened tie member housed within the channel portion and spanning the joint between said ends and engaging and biting into said channel portion when the gripping surfaces are pressed against the diaphragm.

In testimony whereof I have hereunto set my hand.

HORACE LEOPOLD TUCKER BUCKLE.
